(57) **CLAIM**

The ornamental design for a retractable barrier as shown and described.

DESCRIPTION

1. Retractable barrier
2. Retractable barrier
- 1.1 : Perspective
- 1.2 : Front
- 1.3 : Back
- 1.4 : Right
- 1.5 : Left
- 1.6 : Top
- 2.1 : Perspective
- 2.2 : Front
- 2.3 : Back
- 2.4 : Right
- 2.5 : Left
- 2.6 : Top

Broken lines in Figs. 1.3 and 2.3 show portions of the retractable barrier that form no part of the claimed design.
